UNITED STATES PATENT OFFICE.

SAMUEL ARMSTRONG, OF NEWARK, NEW JERSEY.

FRAME FOR POCKET-BOOKS, &c.

SPECIFICATION forming part of Letters Patent No. 230,985, dated August 10, 1880.

Application filed June 28, 1880. (Model.)

To all whom it may concern:

Be it known that I, SAMUEL ARMSTRONG, of the city of Newark, in the county of Essex and State of New Jersey, have invented certain new and useful Improvements in frames for Pocket-Books, Porte-Monnaies, Bags, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to reduce the cost of construction by facilitating the operation and by reducing the heretofore required amount of material; and, further, the object is to produce a novel and pleasing combination of parts.

20 The invention consists in a pocket-book frame peculiarly formed for the reception and retention of the material forming the money-pocket.

It also consists in a spring-clasp having depending ears, one of which is beveled, as shown, which are adapted to unite the two pivoted parts of the frame; and it finally consists in the combination of said frame and said spring-clasp, substantially as in the manner hereinafter more fully set forth and illustrated.

30 Referring to the accompanying drawings, in which similar letters of reference indicate like parts in each of the several figures, Figure 1 is a side view of my invention, showing the manner of uniting the frame with the leather or other appropriate pocket-forming material, and showing the catch. Fig. 2 is a section taken through line *x*, which further illustrates the construction of the catch and the manner of connecting the leather with the frame; and 40 Figs. 3 and 4 show modifications of said manner of connection.

In carrying out my invention, I first strike up with a die or otherwise form the frame A A' with a dentiform inner edge, substantially as shown in Fig. 1, or in its modified form, as in Fig. 3. Between the teeth so formed is placed the pocket-forming material B, alternately before the one and behind the following one, as will be readily understood upon refer-

ence to the drawings, the teeth being bent backward and forward to allow of such operation. The teeth *c* are then pressed back as far as possible into their original position, thereby retaining said pocket-forming material B in a permanent embrace. 50

The teeth *c*, when being stamped out, have left upon their edges a slight burr, which materially aids in holding the said material B, as will be evident; but should said burr be insufficient to retain said material B (as in heavy 60 work) the said teeth may have their edges turned inwardly to accomplish the same purpose, as shown in Fig. 4, the dies being formed accordingly.

I do not confine myself to any particular 65 form of teeth, as any pleasing form may be substituted for the simple square shown in the drawings.

Through the outer portion of the frame A is placed the spring *d*, which is riveted upon the 70 inner side of the frame A by the rivets *e*, and passes through said frame, terminating in the small knob *f*. Upon the spring *d* are secured the depending ears *g*, which are adapted to inclose and unite the parts of the frame A A', 75 one of said ears being beveled or rounded to allow of being automatically raised when the part A' is brought to bear thereon, as will be clearly understood upon reference to Fig. 2.

I am aware that devices have been used previous to this application in which the leather forming the pocket has been clamped and held by portions of the frame; and I am also conversant with the fact that in a broad sense clasps having outside depending ears are not 85 new; but,

Having thus described my invention, what I claim, and wish to have secured by Letters Patent, is—

1. The combination, with the pocket-book 90 or other similar receptacle, of a clasp having outside depending ears, *g*, formed upon a spring, *d*, substantially as and for the purpose set forth and shown.

2. A pocket-book frame having a dentiform 95 or similar inner edge, substantially as herein shown and described, and for the purpose specified.

3. The combination, with a pocket-book, &c., of a spring-clasp with outside depending ears, and the spring thereof riveted upon the inside of the frame, substantially as herein set forth and described.

4. The combination, with a dentiform frame, A A', of a clasp-spring having outside depending ears, g, one of which is rounded or beveled, all being arranged and operating as and for the purpose set forth.

In testimony that I claim the foregoing I have hereunto set my hand this 10th day of June, 1880.

SAMUEL ARMSTRONG.
